O. C. SWAN.

OIL STILL.

APPLICATION FILED APR. 28, 1917.

1,284,945.

Patented Nov. 12, 1918.

UNITED STATES PATENT OFFICE.

OLIVER C. SWAN, OF DENVER, COLORADO, ASSIGNOR, BY DIRECT AND MESNE ASSIGNMENTS, TO THE SWAN PROCESS OIL COMPANY, A CORPORATION OF COLORADO.

OIL-STILL.

1,284,945.

Specification of Letters Patent. Patented Nov. 12, 1918.

Application filed April 28, 1917. Serial No. 165,240.

To all whom it may concern:

Be it known that I, OLIVER C. SWAN, a citizen of the United States, residing at the city and county of Denver and State of Colorado, have invented certain new and useful Improvements in Oil-Stills; and I do hereby declare the following to be a full, clear, and exact description of the invention, such as will enable others skilled in the art to which it appertains to make and use the same.

This invention embodies improvements in oil stills, and while especially useful in connection with purification systems for claiming waste lubricating oils from engines and like sources, as fully set forth in a later filed application now issued as Patent #1,250,526, December 18, 1917, still it may be also effectively employed in the distillation of various grades and kinds of the heavier hydrocarbon oils, as well as the lighter volatile derivatives thereof.

Supplementing this brief reference, the objects and advantages of the present invention will be apparent, as incidental to the following disclosure, without the necessity of further initial statement, but in order to more clearly understand the details of same, reference will now be had to the accompanying drawings; the single view of which illustrates a longitudinal section, taken vertically through the improved type of still, the steam feed and exhaust line pipes being omitted, as it is thought that they are unnecessary to a clear understanding of the invention, which resides in the still itself and associated appurtenances as shown.

The exterior body of the still is preferably formed in three sections, of suitable sheet iron securely bolted or riveted together as usual, and consists of the concave bottom 1, the exterior dome-shaped cover 2 and the intermediate elongated cylindrical section 3.

The bottom 1 is provided with an outlet 4 for withdrawing the residue oil after distillation, and the outer dome-shaped cover 2 is struck up to provide a shallow annular neck 5.

Within this exterior dome-shaped cover 2 is disposed a similar quasi-spherical member 6, substantially spaced therefrom to provide a double wall, and having an annular

neck portion 7, which fits snugly within the short neck 5 of the exterior cover.

A collar 8, having a flanged seating top, fits around the neck 5 and this collar and the necks 5 and 7 are all riveted together, forming a steam tight joint. A similar arrangement is provided at the lower edges of the exterior and interior covers, as indicated at 9, so that the top of the still practically consists of a dome-shaped vapor chamber formed by the double walled cover providing an encompassing jacketed steam chamber 11 therefor.

On top of the flanged collar 8 is seated and bolted a hollow head 12, providing a secondary vapor chamber 13 in open communication with the still, through the space 14, formed by the neck 7, and said dome-shaped vapor chamber.

The top of the hollow head is apertured and is provided with a stuffing box or gland 15, adapted to journal a driven shaft, hereinafter referred to.

The wall of the hollow head 12 is also apertured to receive the outlet conduit pipe 16 for the distillate vapors.

17 simply designates a support opening for a pressure gage, and 18 is a similar arrangement for a thermometer, it not being deemed necessary to actually show a gage and a thermometer, their functioning being clearly understood. I may also state here that the still is equipped with all of the usual appurtenances, not shown in the sectional view, such as relief valves, sight glasses, gage glasses, peep holes, sampling cocks, etc.

19 designates the inlet for the chamber 11, and 20 designates the outlet therefor, which will be further referred to.

I also provide a second jacketed steam chamber 21, interiorly of the still, formed by the annular plate 22, suitably riveted to the interior wall of the cylinder section of the still. The position of this second steam chamber, as is clearly apparent from the drawings, is located at a position immediately between the jacketed dome-shaped vapor chamber and the highest level of the oil, or practically envelops what we may properly term the foam chamber 23. This annular steam jacketed chamber 21 is also provided with an inlet and an outlet, designated respectively at 24 and 25.

In the lower or oil compartment of the still, I arrange a closed steam coil, or preferably a plurality of such coils. In the drawings, I have illustrated two sets of such coils, 5 the upper one being designated by the numeral 26 and the lower one by the numeral 27. These closed steam coils, respectively, have inlets and outlets 28 and 29 and 30 and 31.

10 32 designates an elongated open ended cylindrical well disposed centrally of the coils, being spaced from the bottom 1 of the still, and suitably held in place as by the upper and lower supporting bars 33 15 and 34.

15 Centrally within and spaced from the concave bottom 1 of the still, I mount, in any desired way, a bearing element 35, in line with the aperture of the hollow head and 20 stuffing box or gland 15, which bearing element receives the lower end of a vertical driven shaft 36, the upper end of which passes through said apertured hollow head and stuffing box, and is geared up, as at 37, 25 with any suitable driving means, which may be provided with a controller or governor, not shown.

Secured to the bottom of this shaft and 30 rotating within the concave bottom of the still is an agitating element, comprising a lateral arm 38, projecting on opposite sides of the shaft, and provided with downwardly disposed agitating short paddles or arms 39, for keeping the oil and any water in 35 the bottom of the still in a state of agitation.

Mounted on this same shaft, within the well 32, there is a spiral blade 40 acting as 40 an oil conveyer for elevating the oil up and over the well, for causing complete circulation, as will more fully appear hereinafter.

Toward the upper part of the foam chamber 23 there is fixedly mounted a pair of inwardly projecting supports, provided with 45 upwardly disposed spaced breaker arms 43, and immediately above the same and secured to the shaft 36, is an arm 41 provided with downwardly disposed short breaker arms 42, which alternate with and rotate 50 between the arms 43, coöperating therewith to break up the foam and assist in releasing the volatile vapors contained therein.

The upper end of the shaft 36 carries a 55 smaller spiral vapor conveyer 44, the lower portion of which projects downwardly, through the opening of the double-walled cover, well into said dome-shaped chamber, while the upper portion is reversely disposed in the secondary vapor chamber 13, 60 discharging directly opposite the vapor outlet conduit 16.

During the distillation of these waste oils, the vapors coming off are more or less sluggish, and this small vapor conveyer 44 65 has an effective tendency to spirally elevate

the vapors and start them through the vapor outlet pipe 16 to the condenser. In actual operation, I have observed a wide difference in effectiveness when this small vapor conveyer is used and when it is not.

70 In the concave bottom 1 of the still, and encircling the agitating element 38, is arranged a perforated steam coil 45 adapted for "sweetening" or slightly agitating the oil by jets of incoming steam.

75 This perforated steam coil is supplied with steam, after the still is in full operation, through the exhaust from the jacketed chamber 11.

80 A pipe line 46 leads from the exhaust of the chamber 11, of the cover, to this perforated steam coil, through the branch 47, provided with a valve 48. The pipe 46 continues beyond the branch 47 and is provided with a valve 49, for purposes which 85 will fully appear in the statement of operation.

85 The inner end of the inlet pipe for feeding the oil, to be distilled, into the still is designated at 50, the discharge being just above 90 the bottom of the still, within the circle of the coil 45. This inlet pipe is provided with the usual controlling valve 51.

95 The vapor outlet pipe 16 does not lead directly to the condenser, there being interposed in the conduit line what I term a "catch-all". This consists of a closed vessel 52, into which the vapor outlet pipe 16 discharges, and from which an outlet vapor pipe 53 leads to the condenser, not 100 shown.

105 Within this vessel is disposed a baffle plate 54, which will deflect any spray of oil that might pass out with the vapors to the bottom of the "catch-all", while the vapors pass on around the baffle plate and through the outlet pipe 53 to the condenser.

110 The bottom of this "catch-all" communicates, through a pipe 55, with the still, at approximately the level of the oil therein. This pipe may be provided with a cut-off valve 56, which is normally left open, but it is essential to have a check valve in the line, as at 57, so that when the column of oil in the pipe 55 exceeds the 115 pressure inside the still, the check valve 57 will open and allow the spray oil from the "catch-all" to discharge back again into the still until the opposing pressures again equalize.

120 Operation.

125 As the line pipes for the incoming and exhaust steam may obviously be interchanged at will, it has not been deemed expedient to encumber the drawings with a system of such piping, and it will also be understood that this particular type of still is preferably, although not necessarily, employed in an oil purification sys- 130

tem, the several elements of which are arranged as a plant on different floors of a building, so that the oil being reclaimed flows by gravitation or pumping from one 5 part of the system to the other. Thus the oil inlet pipe 50 is fed from an oil storage reservoir, containing oil which has been previously treated, washed and substantially filtered.

10 In starting up the still, I first cut live steam into the steam chamber 11, of the dome-shaped top, through the inlet 19. At this stage the valve 48, controlling the admission of steam to the perforated coil 45, 15 is closed, and the valve 49 is open.

The incoming steam drives out any waters of condensation, in the chamber 11, through the outlet 20, the pipe 46, and past the valve 49 to a steam trap, not shown, connected up with the boiler.

This is continued until all of the waters of condensation are driven off and good hot steam is passing through the conduit, when the valve 48 is opened and valve 49 closed, 25 so that the live steam will now pass into the perforated coil 45 and issuing in jets therefrom will heat up the interior of the still with "open" steam, which will also heat up the coils 26 and 27 to a high degree, 30 as well as the vapor chamber 13 and vapor outlet 16, preparing the whole still for prompt distillation as soon as the oil is turned in. This preliminary heating with open steam will also prevent pounding in 35 the coils when steam from the pipe line is cut into them.

When the still is thus heated sufficiently to start distillation, the valve 48 is closed and the valve 49 opened, so that while the 40 cover is still maintained at a very high temperature by the steam passing therethrough, the exhaust therefrom will now pass to the steam trap instead of to the interior of the still.

45 Live steam is now cut into the closed steam coils 27 and 26, and the oil valve 51 is opened to allow of the introduction of oil into the still for about two-thirds of its capacity, and at substantially the same time the shaft 36 is started to rotate.

This first charge of oil is then heated up thoroughly, while the oil conveyer screw 40 elevates the oil up through the well 32, where it overflows at the top and falls back 55 again, causing a complete circulation through the heating zone, and providing for a more intimate heating of the molecular particles of the oil body, thus causing rapid vaporization of the lighter volatile substances.

60 As the scum or foam rises on the body of the oil up into the foam chamber 23, steam is also cut into the annular steam jacketed chamber 21, which surrounds the foam chamber, so that this foam is maintained at a 65 very high temperature also, and the revolv-

ing beater arms breaking up this foam further assists in releasing the lighter volatile vapors, which pass on up into the dome-shaped cover. While I have stated that the steam is cut into the annular jacketed chamber 21 when the foam begins to rise, it is obvious that this may be done at the same time that the steam is cut into the closed coils.

The oil vapors, however, are very sluggish 75 in their ascent and would normally condense in the still and fall back again into the body of oil or foam, as in the method of "cracking" distillation. While this is desirably followed where the primary aim is increased 80 production of gasoline or naphtha derivatives, it is to be avoided in refining oils for lubricating purposes, where the aim is to get rid of the naphthas as quickly as possible. By my arrangement the spiral element 44, 85 operating in both said dome-shaped vapor chamber and said secondary vapor chamber, mechanically elevates said vapors bodily through said chambers, forcing them positively out through the pipe 16, substantially 90 accelerating their otherwise sluggish movement, and this, together with the intensive superheating of the double walled cover 2, prevents cracking distillation, or condensation of the oil vapors in the still, after initial 95 vaporization.

These vapors then pass on around the baffle plate 54, in the "catch-all" 52, and pass out through the pipe 53, leading to the condenser, but should any sprays of oil be 100 caused to be sucked out with the vapors they would strike the baffle plate and be deflected to the bottom of the "catch-all" and its lead out pipe to be returned eventually to the still as previously stated.

This initial charge of oil having now been distilled as far as possible, the oil valve 51 is partially opened and set at a position to allow fresh oil to be gradually fed automatically into the still, and as the fresh oil is 110 thus gradually admitted, its lighter volatile constituents are practically vaporized off immediately by the action of the heated oil into which it discharges.

When a full charge has finally been introduced into the still, say to a level slightly below the well top, and after this complete charge has been practically exhausted of its lighter distillates, the valve 49 is again closed and the valve 48 opened to admit the 120 steam from the top chamber 11 to the perforated coil 45, which issuing the same in small jets up through the oil "sweetens" or slightly agitates the oil, and further distillation of the complete charge is continued.

125 As the foam rises in the foam chamber, the action of the beaters 42 thereon and the action of the vapor conveyer 44 is the same as heretofore described, while the steam chamber 11 in the cover and the annular 130

steam chamber 21 surrounding the foam continue to act to maintain the vapors at the upper part of the still in a superheated non-condensed condition.

- 5 The operation is thus continued until the body of the oil has attained the desired flash and fire points, when the still is shut down, and the oil drawn off through the outlet 4 into barrels or other storage receptacle.
- 10 While I have described my improved still with particular reference to the production of a better quality of lubricating oil from waste used oils, after having passed through a purification process, it is obvious that the 15 still itself is not necessarily limited to this particular use.

For instance in obtaining gasolene from crude oils, I might initially employ my still for "cracking" distillation, by passing a 20 cooling medium through the chamber 11, causing the vapors to condense within the still and fall back, which as now understood in refineries increases the final production of gasolene, and then after such "cracking" distillation, the method could be reversed and the still caused to operate as hereinbefore described, so as to get off and condense the vapors as completely as possible.

It will be understood that, although I 30 have shown and prefer to use heating coils interiorly of the still for the oil chamber, I do not except myself from direct exterior heating of the still if deemed expedient in any cases.

35 It is also to be understood that, while I do not limit myself to all of the details as shown, neither do I make any separate claims for well known structural features, of oil stills or degreasing apparatus, for 40 heating and circulating the contents thereof, nor simply for the breaking down or disintegration of arising foam to assist in releasing its condensable vapors, excepting as they may be combined in a novel reorganization 45 of the elements as associated with the more generic principles and features of my invention as disclosed.

What I claim as new and patentable, is:—

1. In an oil still embodying an oil chamber and a foam chamber, with an oil inlet and an oil outlet for the former, in combination with a convex cover, providing an enlarged dome-like vapor chamber extending substantially above said foam chamber as 50 an unobstructed continuation thereof, said cover being of spaced double-wall structure, having a vapor outlet therethrough, to form a jacketed fluid compartment encompassing said vapor chamber; a vapor conduit leading from said vapor outlet; a fluid inlet and a fluid outlet for said jacketed compartment; a jacketed steam compartment encircling the wall of said foam chamber for enveloping the foam therein; means for intensely heating said oil chamber; and a 55

steam inlet and a steam outlet for said second jacketed compartment for superheating the foam encompassed thereby, the whole arrangement functioning substantially as described.

70 2. In an oil still embodying an oil chamber and a foam chamber, with an oil inlet and an oil outlet for the former, in combination with a convex cover, providing an enlarged dome-like vapor chamber extending substantially above said foam chamber as an unobstructed continuation thereof, said cover being of spaced double-wall structure, having a vapor outlet therethrough, to provide a jacketed fluid compartment encompassing said vapor chamber; a steam inlet and a steam outlet for said jacketed compartment; a secondary vapor chamber disposed above said vapor outlet and in open communication with said dome-like chamber 75 through said vapor outlet; a vapor conduit leading from said secondary vapor chamber; an elongated spiral vapor conveyer mounted to rotate in both said dome-like and secondary vapor chambers; means for 80 rotating said vapor conveyer to mechanically assist in bodily elevating the arising vapors through both of said vapor chambers and positively force same through said outlet vapor conduit; and means for intensely 85 heating said oil chamber, the whole arrangement functioning substantially as described.

3. In an oil still the combination with the body of the still, comprising an oil chamber and a foam chamber, said oil chamber having an oil inlet and an oil outlet; means for heating said oil chamber to the degree of vaporizing the volatile constituents of the oil contained therein; a steam jacketed chamber formed interiorly of the still and 100 surrounding said foam chamber; a steam inlet and a steam outlet therefor; a double-walled dome-shaped hollow cover for said foam chamber, providing an enlarged primary vapor chamber encompassed by said 105 steam jacketed cover; a steam inlet and a steam outlet for the latter; a secondary vapor chamber surmounting said steam jacketed cover, in direct communication with the dome-shaped space thereof; a vapor outlet pipe therefor; a driven shaft extending through said still and vapor chambers, circulating means mounted at the bottom of said shaft; beater arms mounted on said shaft in said foam chamber; and an elongated vapor elevating screw conveyer mounted at the top of said shaft and operating in both of the said vapor chambers, substantially as described.

4. In an oil still the combination with the 115 body of the still comprising an oil chamber and a foam chamber, said oil chamber having an oil inlet and an oil outlet; of means for heating said oil chamber to a degree of vaporizing the volatile constituents of the 120

oil contained therein; a steam jacketed dome-shaped cover for said foam chamber, provided with a vapor outlet; a steam inlet and a steam outlet for said steam jacketed 5 cover; an exhaust pipe leading from said steam outlet, and provided with a control valve; a perforated steam coil in the bottom

of said still; a branch pipe connecting said perforated coil with said exhaust pipe between said cover outlet and said valve; and 10 a control valve in said branch pipe, substantially as described.

In testimony whereof, I affix my signature.
OLIVER C. SWAN.
